UNITED STATES PATENT OFFICE.

GEORGE W. THOMPSON, OF SPRINGFIELD, MISSOURI, ASSIGNOR OF THIRTY-TWO ONE-HUNDRED-AND-TWENTY-EIGHTHS TO WILLIAM B. SANFORD, TWENTY-FOUR ONE-HUNDRED-AND-TWENTY-EIGHTHS TO DOUGLAS J. LANDERS, TWENTY-ONE ONE-HUNDRED-AND-TWENTY-EIGHTHS TO WILLIAM A. MCATEE, TWELVE ONE-HUNDRED-AND-TWENTY-EIGHTHS TO ALPHONSO B. LOVAN, TWELVE ONE-HUNDRED-AND-TWENTY-EIGHTHS TO GEORGE W. YOUNG, AND THREE ONE-HUNDRED-AND-TWENTY-EIGHTHS TO WILLIAM T. SHORES, ALL OF SPRINGFIELD, MISSOURI, AND SIX ONE-HUNDRED-AND-TWENTY-EIGHTHS TO CLARENCE H. NICHOLS, OF NEW YORK, N. Y.

ACETYLENE-GAS GENERATING AND SUPPLY SYSTEM.

1,272,727.

Specification of Letters Patent. Patented July 16, 1918.

Application filed December 8, 1917. Serial No. 206,167.

To all whom it may concern:

Be it known that I, GEORGE W. THOMPSON, a citizen of the United States, residing at Springfield, Greene county, Missouri, 5 have invented a new and useful Acetylene-Gas Generating and Supply System for Automobiles, of which the following is a specification.

The present invention is an acetylene gas 10 generating and supply system for automobiles.

An object of the invention is to provide an efficient system for generating the acetylene gas and supplying the same to the engine of an automobile in quantities sufficient 15 to maintain the engine in constant operation when desired so that the vehicle will be propelled by the engine operating with acetylene gas. In this connection it will be understood, of course, that the system for generating and supplying the acetylene gas is 20 equipped with proper controlling devices for controlling the supply of the gas to the engine in order that the operation of the 25 engine may be under complete control of the operator.

Another object of the invention is to provide a system for generating and supplying acetylene gas to the engine of an automobile, 30 including mechanism controlled and operated by the engine for controlling the supply of carbide to the generator so that the quantity of gas generated will be commensurate and properly proportioned to the quantity 35 of gas consumed by the engine and required to maintain the engine in proper operation, so that the quantity of gas generated will be varied in accordance with the variation in the amount of gas consumed.

Another object of the invention is to provide a system for generating and supplying acetylene gas to the engine of an automobile, 40 said system including efficient safety and controlling devices for efficiently controlling the supply of gas and for preventing backfire into the supply system.

Other objects which do not reque-

cific mention in this connection will appear from the following description read in connection with the drawings, in which—

Figure 1 is an elevation, diagrammatic in form, illustrating the generating and supply system applied to an automobile, it being understood that the location of the various parts of the generating and supply system 55 may be varied as desired or required by the type or construction of automobile with which the system is combined.

Fig. 2 is a view illustrating certain essential parts of the invention in section and 60 others in elevation, certain of the connecting pipes and parts being broken to permit the different parts of the system to be illustrated in proximity to each other.

Fig. 3 is a sectional view of the carbide, 65 container on the line 3—3 of Fig. 2 viewed in the direction of the arrows.

Fig. 4 is a sectional view on the line 4—4 of Fig. 2 looking in the direction of the 70 arrows.

Fig. 5 is a sectional view of a seal device included in the supply passage between the generator and the carburetor.

Fig. 6 is an enlarged sectional view of a 75 pressure reducing valve included in the system.

Fig. 7 is a detailed view of a clutch constituting a part of the connections operated by the engine for delivering the carbide into the generating tank.

Fig. 8 is a sectional view of a check valve 80 in the pipe between the generating tank and the storage tank.

Fig. 9 is a sectional view of the device for controlling the clutch in the connections operated by the engine for delivering the carbide into the generating tank.

Fig. 10 is a sectional view of the pressure relief device by which excessive pressure is released from the generating tank in case of 90 generation of an excessive supply of gas creating over-pressure.

In the embodiment illustrated the generating tank 1 is supported in an appropriate

place by the automobile and contains a quantity of water into which the carbid is delivered. Above the generating tank is a receptacle 2 for the carbid, said receptacle having 5 a removable cover in order that the carbid may be placed within the receptacle as desired.

The bottom of the receptacle 2 includes a bottom wall 3 having two openings 4, and 10 below the bottom wall 3 there is a plate 5 having a pair of spaced openings 6 out of alignment with the openings 4. A revoluble disk 7 is mounted between the bottom 3 and the plate 5 and is provided with a pair of 15 openings 8 which, as the disk is rotated, are brought into alternate registration with the openings 4 and the openings 6. Thus the carbid which is in small particles constantly fills the openings 4 in the bottom of the 20 carbid receptacle; and when the openings 8 in the revoluble disk are brought into alignment with the openings 4 as the disk is rotated quantities of the carbid enter the openings 8, and as the disk rotates such quantities 25 of carbid as enter the openings 8 are moved around with the disk 7 until said openings 8 register with the openings 6, whereupon the carbid in the openings 8 drops through the openings 6 into the water 30 in the generating tank. The disk 7 is rotated by the engine so that the quantity of carbid delivered into the generating tank is in proportion with the quantity of gas being consumed by the engine.

35 In the embodiment illustrated, which may be varied in accordance with the individual preference or different requirements, the disk 7 is driven by connections operated by the usual pump operating shaft 9 which as 40 usual is operated by the crank shaft of the engine. As shown the shaft 9 is provided with a pinion 10 which meshes with a pinion 11 on a shaft 12 supported in appropriate bearings under or in connection with the 45 vehicle body. A vertical shaft 13 (Fig. 2) extending through the generating tank is keyed to the disk 7 so that when the shaft 13 is rotated the disk 7 rotates therewith. The lower end of the shaft 13 supports a 50 beveled gear 14 meshing with a beveled gear 15 attached to a shaft 16 in alignment with the shaft 12, and adapted to be connected with and disconnected therefrom by a clutch device. This clutch device is illustrated in 55 Fig. 7. One member 17 of the clutch device is attached to the shaft 12 and the cooperating parts are supported by the shaft 16. To a support 18 attached to the shaft 16 a pair 60 of clutch levers 19 are pivoted and are provided with shoulders 20 adapted to be moved into and out of engagement with the members 17 to clutch the shaft 12 with the shaft 16. The ends of the levers 19 are pivoted to a collar 21, movable axially on the shaft 16 65 and actuated toward the clutch member 17

by a spring 22. Thus the shaft 12 and the shaft 16 are normally connected or clutched together, so that when the shaft 12 is rotated by the engine the shaft 16 will also be rotated normally.

70 Provision is made whereby the clutch will be automatically disengaged when the pressure of gas in the generating tank rises beyond a predetermined maximum, that is when the gas supply rises above the quantity 75 being consumed or demanded by the engine. The device for disengaging the clutch and releasing the shaft 16 from the shaft 12 is operated automatically and in the embodiment illustrated includes connections operated 80 by the gas pressure for moving the collar 21 axially on the shaft 16 in a direction away from the clutch member 17 in order to move the shoulders 20 out of contact with the clutch member 17, and I will now describe these connections.

A passage 23 (Fig. 9) from the generating tank opens into a chamber 24 in which there is a diaphragm plate 25 constituting a support for the base of a rod 26. A lever 27 is pivoted to a support 28 and is connected to the rod 26 as shown. A link 29 connects the lever 27 with one arm of a bell crank lever 30 (Figs. 2 and 7), the opposite arm of the bell crank lever being connected in a 95 well understood manner with the collar 21, so that by operation of the bell crank lever in one direction, the collar will be moved axially on the shaft 16 to operate the levers 19 and release the clutch. Thus, when the 100 pressure or quantity of gas in the generating tank rises to a predetermined maximum, the diaphragm 25 is raised, the rod 26 is moved, the lever 27 is operated, and the link 29 operates the bell crank lever 30 to 105 move the collar 21 in opposition to the spring 22, as required to release the clutch and disconnect the shaft 16 from the shaft 12. This leaves the shaft 12 in constant rotation while the engine is running without 110 operating the shaft 16 and consequently the disk 7 is stopped, and no more carbid is delivered into the generating tank until the clutch connection is restored and the shaft 16 is again rotated as an incident to the reduction of the quantity of gas in the generating tank.

115 A pipe 31 constitutes a passage from the generating tank to a storage tank 32 through which the gas is conducted from the generating tank to the storage tank. A check valve is included in the passage 31 to prevent back pressure or backward flow of the gas from the storage tank in case the generating tank is opened. The check valve is 120 illustrated in Fig. 8 and comprises a valve case 33 having a partition 34 between the inlet and outlet passages of the case. The partition 34 is provided with an opening in 125 which operates the stem 35 of a valve 36. 130

When the pressure in the storage tank 32 is lower than the pressure in the generating tank the valve 35 is opened by the pressure of the gas from the generating tank, thus 5 permitting the gas to pass into the storage tank. When the pressure of the gas in the storage tank equals that in the generating tank, the valve automatically closes, and in case the pressure in the generating tank is 10 reduced by any cause, the valve is held in closed position by the pressure of the gas.

A pipe 37 leads from the storage tank 32 to a tank 38 and is equipped with a pressure reducing valve so that the gas will not be 15 forced toward the engine under too great pressure. The pressure reducing valve is illustrated in Fig. 6 and includes a case 39 having a chamber 40 formed therein, into which the gas is admitted from the tank 32. 20 The chamber 40 has an outlet opening 41 in which is seated a needle valve 42 in connection with a valve member 43 supported by a spring 44. The valve is opened by the pressure of the gas from the tank 32 only 25 when the pressure of the gas in the tank 38 becomes reduced to a predetermined minimum. The amount of pressure required to open the valve 42 may be varied and in the form shown the device for varying the resistance of the spring comprises a spring 45 bearing against a lower member 46 which is seated upon a diaphragm 47 that bears against the valve support 43. A screw 48 operates against a disk 49 against which the upper 35 end of the spring 45 bears, so that by adjustment of the screw in different positions the pressure of the spring 45 in opposition to the pressure of the spring 44 may be varied.

The pipe 37 also includes a valve 50 of 40 usual construction which may be adjusted in order to close the passage 37 entirely, and prevent any gas passing from the tank 32 into the tank 38.

A passage 51 from the tank 38 opens into 45 the case 52 of a water seal device (Fig. 5), the lower and open end of the pipe 51 being submerged in the water in the case 52. A float 53 seats against the lower open end of the pipe 51 in the case 52, but yields to the 50 pressure of the gas when the engine is operating to permit the gas to be discharged from the pipe 51 into the water in the case 52 from which the gas, after rising through the water, passes through a pipe 54 into a carburetor 55 and thence into the manifold 56 of the engine.

A passage 56 from the tank 32 is connected with an indicator 57 supported in convenient position upon the dash of the automobile to indicate to the operator of the vehicle the pressure in the storage tank. Similarly, a passage 58 from the tank 38 60 leads to an indicator 59 on the dash of the vehicle for indicating to the operator the amount of pressure in the reducing tank 38.

Provision is made for releasing the pressure in the generating tank automatically in case the pressure rises beyond a desired maximum. As shown the device for effecting this result includes a discharge passage 70 60 (Fig. 10) opening into a valve case 61 having an exhaust outlet 62 and a partition 63 between the exhaust outlet and the inlet. An opening is formed in the partition 63 and is controlled by a puppet valve 64 in 75 connection with a stem 65 extending through the upper wall of the case and having a projection 66 thereon. A lever 67 is pivotally supported at 68 and has one end thereof seated upon the projection 66 so that the 80 valve will be normally pressed to and held in closed position by said lever. A spring 69 presses against the lever 67 and serves to hold the valve 64 closed until the pressure in the generating tank rises beyond the desired 85 maximum, whereupon the pressure of the gas against the valve 64 overcomes the pressure of the spring 69 and opens said valve and thus relieves the pressure in the generating tank.

From the foregoing it will be apparent that my improved system includes gas generating means controlled or operated directly by the engine, and that the gas generated as a result of the operation of the 90 generating means passes to and causes operation of the engine. Thus there is a complete and direct coördination and coöperation between the engine and the gas generating means, and the latter being controlled 95 from the engine operates in harmony with the engine so that only the required amounts of gas forming materials are consumed. I do not restrict myself to the specific mechanism for controlling the generating means 100 from the engine, nor to any specific features of construction and arrangement other than set forth in the appended claims.

What I claim and desire to secure by Letters Patent, is:—

1. The combination with the engine of a vehicle, of an acetylene gas supply system supported by the vehicle and comprising a tank arranged to contain one of the gas forming materials, a generating tank arranged to contain another of the gas forming materials, mechanism for delivering the gas forming material from the first-mentioned tank into the generating tank, a shaft driven by the engine, a shaft for operating 110 said mechanism, a device settable in one position to drive the second-named shaft from the first-named one and settable in another position to enable the first-named shaft to operate while the second shaft remains idle, 115 automatic means for moving said device to position to drive the second shaft from the first one, and means operated by the pressure of the gas in the generating tank for moving said device to position to enable 120 125 130 135 140 145 150 155 160 165 170 175 180

- the second-named shaft and said mechanism to remain idle while the first-named shaft continues to operate.
2. The combination with the engine of a vehicle, of an acetylene gas supply system supported by the vehicle and comprising a tank arranged to contain one of the gas forming materials, a generating tank arranged to contain another of the gas forming materials, mechanism operated by the engine for delivering the gas forming material from the first-mentioned tank into the generating tank, a passage for conducting the gas generated in the generating tank to the engine, and means controlled by the pressure of the gas in the generating tank for rendering said mechanism inoperative when the pressure of the gas in the generating tank exceeds a predetermined maximum.
3. The combination with an engine, of an acetylene gas supply system for the engine comprising a tank arranged to contain one of the gas forming materials, a generating tank arranged to contain another of the gas forming materials, mechanism for delivering the gas forming material from the first-named tank into the generating tank, a device operated by the engine for operating said mechanism, and means controlled by the pressure of the gas in the generating tank for preventing operation of said mechanism by said device when the pressure of the gas in the generating tank exceeds a predetermined maximum.
4. In a gas supply system, the combination of a gas generating tank, a storage tank, a passage between said gas generating tank and said storage tank, a second storage tank, a passage between said first-named storage tank and said second-named storage tank, a passage for conducting the gas from
- the second-storage tank, and a float device controlling said last-named passage.
5. In a gas supply system, the combination of a gas generating tank, a storage tank, a passage between said gas generating tank and said storage tank, a second storage tank, a passage between said first-named storage tank and said second-named storage tank, a pressure reducing valve in said last-named passage, a passage for conducting the gas from the second storage tank, and a float device controlling said last-named passage.
6. In a gas supply system for an engine, the combination with the engine of a gas generating tank, a material tank for containing gas generating material, a passage between said material tank and said gas generating tank, automatic means for delivering material from said material tank to said gas generating tank, driving mechanism for actuating said automatic means, a storage tank, a passage between said gas generating tank and said storage tank, and a clutch device operated by the pressure in said gas generating tank for rendering inoperative the mechanism for driving said automatic means when a predetermined gas pressure has been attained in said gas generating tank.
7. In a gas supply system, the combination with an engine, of a gas generating tank, a gas generating material tank in communication with said gas generating tank, a feed device between the material tank and the gas generating tank, automatic mechanism operated by the engine for operating said feed device, and a controlling device for said operating mechanism operated by the pressure in said gas generating tank.

GEORGE W. THOMPSON.
